UNITED STATES PATENT OFFICE.

GEORGE WASHINGTON BELL, OF ST. JOSEPH, MISSOURI, ASSIGNOR OF ONE-HALF TO JOHN O. STEPHENS, OF SAME PLACE.

TRUSS.

SPECIFICATION forming part of Letters Patent No. 392,983, dated November 20, 1888.

Application filed November 25, 1887. Serial No. 256,142. (No model.)

To all whom it may concern:

Be it known that I, GEORGE WASHINGTON BELL, a citizen of the United States, residing at St. Joseph, in the county of Buchanan and State of Missouri, have invented new and useful Improvements in Trusses, of which the following is a specification.

My invention relates to improvements in trusses; and it consists in certain novel features, hereinafter described and claimed.

In the annexed drawings, Figure 1 is a perspective view with the belt shown partly in section. Fig. 2 is a longitudinal section of the electric adjustable pad and the means for adjusting the same. Fig. 3 is a detail perspective view of one of the improved adjustable arms, showing a pressure-pad attached thereto. Fig. 4 is a sectional view of the ordinary pressure-pad.

Referring by letter to the drawings, A designates the band of the truss, on the rear end of which is adjusted the pad B. A spindle, C, is attached to the front end of the band, and on this spindle is arranged the socket D. It will be seen that this socket may be turned at will around the spindle and secured in any desired position by set-screws, provided for the purpose, which pass through the sides of the socket and impinge at the inner ends against the spindle.

E designates a plate, which is formed on the outer end of the socket D, and it is provided with a central tapped opening or aperture, F.

G represents a flat spring, which is arranged over the plate E, and is provided with a central aperture, H, to register with the opening F. A set-screw, I, is passed through the opening H and engaged in the tapped opening, whereby when the former is screwed in the

spring is drawn firmly toward the plate E. The said spring normally stands away from the plate, as shown in dotted lines in the section, Fig. 2. A series of perforations, K, are formed in the spring G, near the outer edge, and they are arranged in a semicircle around the set-screw.

L designates the adjustable arm of the truss, which is provided at one end with the ear M, which is provided with a central aperture, N, to register with the apertures in the plate E

and spring G and receive the set-screw which is engaged in the said apertures. The adjustable arm may be turned around the said set-screw to assume any desired position, and it will be seen that if the set-screw is tightened the spring will be drawn down and bind the said arm in the desired position.

O represents a pin, which is arranged on one side of the ear M in such a position that it will engage in either of the perforations in the spring G, and therefore when the said spring is drawn down by the set-screw this pin is locked in one of the perforations and the arm cannot be moved until the spring is allowed to rise to free the pin.

P designates a pad having an annular body, Q, provided on the outer side with an annular shoulder, R. A spiral spring, S, bears at the outer edge on this shoulder, and it is securely bound in place by the annular plate T, which is secured on the outer side of the body Q.

V designates a collar arranged on the adjustable arm L and adapted to slide thereon, and it is provided with set-screw v, to enable the same to be clamped at the desired point on the arm. This collar is provided with a spindle, U, which is attached to the center of the said spiral spring, so that the pad may be rotated to enable it to be properly adjusted to the shape of the portion of the body against which it is designed to bear. It will be seen that the spring, arranged as described, in the pad will allow the latter to rock in all directions, so that as the person moves the pad will not rub and irritate the flesh. This rubbing, if allowed to continue, will produce inflammation, which will reduce the advantages which might be derived from the use of a truss. There is no irritation of the parts when this pad is employed.

The means of adjustment of the pad will now be seen. The socket may be rotated on the spindle C, the adjustable arm may be arranged at any desired angle to the band, the pad may be adjusted at any point of the length of the said arm, and may also be rotated thereon. A copper plate, X, is secured on the inner side of the annular body of the pad, a zinc plate, Y, is arranged on the outer side of the copper plate, and felt insulation Y' is dis-

posed between the plates to cut off all electrical connection. An opening is formed in the center of the copper plate, and a copper wire, Z, passes through the side of the annular body and up through the said central opening in the copper plate to form an electrical connection with the zinc plate. The end of the wire Z on the outer side of the body Q is formed into a loop, z, for a purpose to be described.

The ordinary pressure pad, a, which is shown in Fig. 4, is constructed very similar to the electric pad just described. It comprises the annular body b, having a shoulder, c, on the outer side, the spiral spring d, seated on this shoulder, the annular plate e, secured on the outer side of the body b, to hold the spring in place, the said spring being attached at the center to a spindle, which is formed on the adjustable collar to be applied to the adjustable arm. A cushion, k, is arranged on the inner side of the annular body, and the entire body and cushion are enveloped in a casing, l, of chamois-skin or other suitable material. It will be understood that either of these pads may be attached to the truss.

A' designates the electric belt, comprising the casing B', of leather or other suitable and preferred material, and the battery D', enclosed within the said casing. The battery consists of a series of cells of copper and zinc arranged alternately and indicated, respectively, by the letters C' and Z'. These cells are connected together by the copper wires G' G', which are laced through the said rolls and pass, respectively, upon opposite sides of the insulating-pads.

K' designates an electrode, which is connected to one end of the battery by means of the copper connecting-wire M'. The wire M' is integral with the wire M, and is connected at its free end to the rear end of the truss-band in any preferred manner, but preferably by forming a loop in the end thereof and engaging it over any suitable screw on the rear pad. The wire L', which is attached to the opposite end of the battery, is provided at the end with a hook which is engaged in the loop z on the side of the pad P. It will thus be seen that the one end of the battery is connected electrically with the zinc plate on the face of the adjustable pad.

The construction of the battery and the details of its connection with the truss are made the subject-matter of a separate application, and therefore are only mentioned herein to enable the present invention to be more readily understood.

It will now be seen that the electrode K' will bear against the body near the rear end of the truss and the electric pad P will bear on the diseased part, and the current will flow through these two poles and pass directly through the rupture.

It is evident that the electric belt may be readily removed to allow the remainder of the device to be used as an ordinary truss.

The electric pad herein described is included in the drawings and description of this case to show that the improved means for adjusting the pad may be applied with advantage to electric pads as well as to ordinary pressure-pads.

Having thus described my invention, I claim—

1. In a truss, the combination of the band A, a plate, E, and the spring G at one end thereof, the set-screw to draw the spring and plate together, the adjustable arm L, pivoted on the set-screw between the spring and plate, and the pad attached to the arm L, all constructed and arranged substantially as specified.

2. In a truss, the combination, with the band A, having the plate E on one end thereof, of the spring G, attached to the said plate and having a series of perforations, K, the adjustable arm L, having its inner end fitted between the spring and the plate, the set-screw I, to draw the spring and plate together, the pin O on the arm L, to engage the perforations K, and the pad attached to the arm L, substantially as specified.

3. In a truss, the band A, having the spindle C, the socket D, fitted on the spindle so that it may be turned at will around the spindle, the clamping device to hold the socket at any desired position, the arm L, pivoted to the socket D and capable of angular adjustment independent of the socket, the collar V, disposed on the arm L and provided with a set-screw whereby the collar is capable of axial and longitudinal adjustment on the arm L, and the pad swiveled to the spindle U, connected to the collar V, so that the pad may be turned or rotated, as set forth.

4. The herein-described pad comprising the body having an angular shoulder on its rear side, the flat coiled spring having its coils nested together one within the other in the same plane, the outer coils bearing on the pad within the shoulder, the plate secured to the body and projecting over the outer coils to confine them in place, and the spindle U passed through the center of the spring and swiveled, as set forth.

5. In a truss, the combination, with the band having a spindle, C, on one end, of the socket D, mounted on the spindle and having set-screws to impinge at their ends against the spindle, the said socket having a plate, E, at its free end provided with a central tapped aperture, F, the spring G, mounted on the socket adjacent to the said plate and having an aperture, H, therein aligning with the aperture F, the set-screw mounted in the aligned apertures, the movable arm L, mounted on the said screw between the spring and the adjacent plate, and the pad attached to the arm L, substantially as and for the purpose specified.

6. In a truss, the combination, with the band having a rigid spindle, C, on one end, and the socket D, adjustably mounted on the

spindle and having a plate, E, provided with the central aperture, F, of the spring G, secured to the socket D, adjacent to the said plate, and having a central aperture, H, aligned 5 with the aperture F, and the semicircular series of perforations K, arranged around the central aperture, the set screw I, engaging the aligned apertures, the arm L, mounted on the set-screw between the spring and the plate 10 and having a pin, O, on its outer side engag-

ing in one of the perforations K, and the pad attached to the said arm, substantially as and for the purpose specified.

In testimony that I claim the foregoing as my own I have hereto affixed my signature in presence of two witnesses. 15

GEORGE WASHINGTON BELL.
